UNITED STATES PATENT OFFICE.

ARTHUR MOSER, OF NORTHAMPTON, PENNSYLVANIA.

HYDRAULIC BRAKE-OPERATING MEANS.

Application filed November 3, 1927. Serial No. 230,773.

The invention relates to hydraulic vehicle brakes and specifically to operating means for the brake units associated with the wheels. Prior to my invention, an operating means has been devised embodying two parallel cylinders connected by pipes with the brake units, two fluid-forcing pistons in said cylinders, two piston rods projecting from said pistons beyond one end of the cylinders, an operating member at the outer ends of said piston rods, and equalizing means between said operating member and said rods. The construction of the equalizing means however has been such as to exert 15 severe lateral stress upon the piston rods, if one of them is permitted, for instance by leakage, to advance considerably ahead of the other rod. It is the aim of my invention to provide new and improved equalizing 20 means whereby this difficulty is effectively overcome.

With the foregoing in view, the invention resides in the novel subject matter herein-after described and claimed, the description 25 being supplemented by the accompanying drawings.

Fig. 1 is a sectional view partly in elevation showing the invention in the relation with other parts, assumed when the two piston rods advance uniformly.

Fig. 2 is a view similar to Fig. 1 but showing the manner in which the improved equalizing means compensates for non-uniform advance of the piston rods.

Fig. 3 is a sectional perspective view illustrating a modified form of equalizing means, this view being principally for the purpose of showing that the pivotal and combined pivotal and slidable connections between the operating member, equalizing lever and piston rods, need not be of the forms shown in Figs. 1 and 2.

In the drawings above briefly described, the numerals 4 denote two parallel cylinders connected by appropriate piping 5 with the brake units (not shown) and connected by additional piping 6 with a feeder tank (not shown). Slidable in these cylinders, are two pistons 7 whose parallel piston rods 8 extend through bosses 9 at one end of said cylinder. At the rear ends of these rods ("rear" being used with reference to the operative or advancing movement of the pistons and rods rather than with regard to the vehicle) is an operating member 10 preferably in the form of a push rod having

suitable connection with the usual brake pedal (not shown). The improved equalizing means is provided to connect the operating member 10 with the rods 8 and the 60 preferred construction disclosed in Figs. 1 and 2 will first be described.

The rear ends of the rods 8 are provided with forks 11 and with pivot pins 12 extending across said forks. Similarly, the front end of the operating rod 10 is provided with a fork 13 and with a pivot pin 14 extending across said fork. A flat equalizing lever 15 passes through the three forks 11-13 and projects laterally beyond said forks 11, the 70 central portion of said lever being formed with an opening through which the pivot pin 14 passes, while the end portions of said lever are provided with slots 16 through which the pivot pins 12 pass. These slots 75 are so spaced that when the lever 15 is at right angles to the rods 8, the pins 12 are seated against the inner end walls 17, so that forward movement of the rod 10 will exert a direct forward pressure upon the rods 8, 80 having no tendency whatever to exert any lateral stress upon these rods. In this connection, attention is invited to the fact that the slots 16 widely diverge forwardly. These slots are preferably longitudinally 85 curved as shown.

The pivot 14 connecting the rod or the like 10 with the lever 15, is preferably disposed in advance of a line intersecting the pivots 12 so that the forward push on said 90 rod will have no tendency to tilt said lever 15 about an axis extending longitudinally of said lever.

If for any reason such as a leak in the piping 5 connected with one of the cylinders 95 4, the piston 7 and rod 8 of this cylinder are permitted to advance more rapidly than the other piston and rod, compensation for such differential movement is provided by the equalizing lever 15, and regardless of the 100 difference in travel of these rods, the fluid-forcing pressure thereon will be so exerted as to cause no lateral stress upon the rods, with consequent danger of binding them or of causing springing thereof. Preferably, 105 when either rod 8 moves inwardly to the maximum, its movement is limited by contact of its fork 11 with the adjacent boss 9, but it is to be understood that this particular limiting means is not essential as some other 110 could well be provided.

In the construction shown in Fig. 3, the

rear ends of the rods 8 are formed with eyes 18. These eyes loosely receive the ends of a bow-shaped equalizing lever 19. The front portions of the eyes 18 constitute pivots corresponding to the pivots 12 and the end portions 20 of the lever 19 which diverge forwardly from the rods 8, contact with the rear sides of these pivots and correspond to the portions 15^a of the lever 15, contacting with the rear sides of the pivots 12 and diverging forwardly from the piston rods. The lever 19 is formed with stops 21 at the inner sides of the eyes 18, corresponding to the slot ends 17 above described.

15 The operating member or rod 10 in Fig. 3 is provided with a fork 22 whose crotch 23 is of substantially V-shape to engage a seat 24 at the center of the lever 19, establishing a pivotal connection between said lever and the rod 10. Rearward movement of rod 10 with respect to lever 19 may be prevented by a pin 25 connecting the fork arms and disposed in front of said lever. As in the form of construction previously described, the pivotal connection between the operating member or rod 10 and the lever 19, is in advance of the pivots forming parts of the means for establishing combined pivotal and slidable connections between said lever and the piston rods 8. As previously stated, the construction shown in Fig. 3 is embodied principally to illustrate that the pivotal and combined pivotal and slidable connections need not be of the forms shown in Figs. 1 and 2, and it will be understood that variations in construction other than those herein illustrated, may be made within the scope of the invention as claimed.

I claim:

40 1. In a hydraulic brake operating means, two parallel piston rods, a transverse equalizing lever extending transversely between the outer ends of said piston rods, two combined pivotal and slidable connections con-

necting said equalizing lever with said rods 45 and permitting swinging of said lever in either direction about the pivots of said connections and also allowing sliding of said lever transversely of the rods incident to such swinging, and an operating member 50 having a pivotal connection with the central portion of said lever.

2. A structure as specified in claim 1; the pivotal connection between said operating member and said equalizing lever being in 55 advance of said pivots of said combined pivotal and slidable connections.

3. In a hydraulic brake operating means, two parallel piston rods having pivots at their rear ends, an equalizing lever extending transversely between said rods, said lever having end portions which project laterally from said rods, abut the rear sides of said pivots and diverge forwardly from said rods, and an operating member having a 65 pivotal connection with the central portion of said lever.

4. A structure as specified in claim 3; said pivotal connection being in advance of said pivots.

5. In a hydraulic brake operating means, two parallel piston rods having forks at their rear ends and pivot pins passing across said forks, an equalizing lever extending transversely between said forks and passing through and beyond the same, the end portions of said lever being formed with slots which diverge forwardly and receive said pivot pins, and an operating member having a pivotal connection with the central portion 80 of said lever.

6. A structure as specified in claim 5; said pivotal connection being in advance of said pivot pins.

In testimony whereof I have hereunto 85 affixed my signature.

ARTHUR MOSER.
